UNITED STATES PATENT OFFICE.

WILLIAM B. WICKES, OF SHARON, MASSACHUSETTS.

CLOTHES-POUNDER.

SPECIFICATION forming part of Letters Patent No. 228,846, dated June 15, 1880.

Application filed February 24, 1880.

To all whom it may concern:

Be it known that I, WILLIAM B. WICKES, of Sharon, in the county of Norfolk and State of Massachusetts, have invented certain Improvements in Clothes-Pounders, of which the following is a specification.

This invention relates to that class of clothes-pounders in which a cylinder with two perforated heads and a piston working between said heads are employed, the piston having a rod which serves as a handle to operate the pounder.

My invention has for its object to enable the cylinder to be rotated by the piston-rod, so that it may be conveniently freed in case fabrics become wound about the body or entangled with the perforated body of the cylinder, a shield being employed to prevent water from being squirted upwardly from the top of the cylinder.

My invention consists in the improvements which I will now proceed to describe and claim.

Of the accompanying drawings, forming a part of this specification, Figure 1 represents a side elevation of my improved clothes-pounder. Fig. 2 represents a section on line *x x*, Fig. 3 represents a section on line *y y*, Fig. 1.

The same letters indicate the same parts in all the figures.

In the drawings, A represents the cylinder forming the body of the clothes-pounder, said cylinder being made of sheet metal and provided with perforated cast-metal heads B B', through which water will freely pass. The heads are rigidly attached to the ends of the cylinder, and the upper head, B', has an upwardly-projecting tube, C, rigidly attached to it.

D represents the piston, located between the heads B B', and consisting of a single plate having a central perforation, through which passes a screw, E, attaching the piston to the end of the rod F, so that the piston can be readily detached, if desired. The rod F passes through and is adapted to reciprocate longitudinally in the tube C, and thus reciprocate the piston. The rod F also serves as a handle to move the cylinder and its attachments.

G represents a longitudinal slot formed in the rod F, and H represents a pin attached to the tube C and passing through the slot G. The slot is of sufficient length to permit the reciprocating movement of the rod and piston. 55

It will be seen that with the slot and pin the operator, while standing in the usual position, can use the rod as a handle to rotate the pounder as well as to operate the piston and move the pounder about. 60

I represents a shield, which is placed over the upper end of the cylinder to arrest water thrown up by the operation of the pounder. The central part of the shield is dome-shaped and is attached to the tube C. The margin of 65 the shield has a downwardly-projecting flange, J, which projects below the upper end of the cylinder, so that it more effectually prevents the lateral discharge of water from the upper end of the cylinder than heretofore. 70

K K represent arms connecting the flange J with the upper end of the cylinder. These arms brace and support the flange J, and prevent the shield from being knocked out of place, and also prevent the fabrics being 75 washed from being drawn into the space between the flange and the upper end of the cylinder by the downward movement of the piston, which gives the water and fabrics a tendency to enter the upper end of the cylinder. 80 The shield and the arms K strengthen the connection of the cylinder to the upper head, B', and prevent the cylinder from being displaced.

I claim—

The within-described clothes-pounder, composed of the cylinder A, its perforated heads B B', the tube C, rising from head B', the rod F, slotted and secured to the tube C by a pin, H, passed through the slot and tube, the piston D, removably attached to said rod, and a shield, J, all constructed, arranged, and combined substantially as shown. 85

In testimony whereof I have signed my name to this specification, in the presence of two subscribing witnesses, this 21st day of 95 February, A. D. 1880.

WILLIAM B. WICKES.

Witnesses:

C. F. BROWN,
J. P. COLLINS.
